LAY FOR WEAVING LOOMS

Walter A. Sherwood, Hempstead, and Thomas D. Verrill, Farmingdale, N.Y., assignors, by mesne assignments, to Farmingdale Manufacturing Corporation, Baltimore, Md., a corporation of Maryland

Application October 17, 1956, Serial No. 616,403

11 Claims. (Cl. 139—188)

This invention relates to a lay for weaving looms and particularly to the lay support and cam assembly, for use with a loom in which the shuttle boxes are fixed on the loom frame.

An object of the invention is to provide means to beat up the filling faster and with a much shorter swing of the lay, making possible a relatively long dwell of the lay after beat-up in the position where the shed is open to form a clear passage for the shuttle throughout its entire flight, thus eliminating shuttle marks and reducing wear on the shuttle and reeds, while making it practical to use a lighter shuttle.

Another object is to provide positive and accurate positioning of the reed on the lay when beating up and when at dwell.

A further object is to provide a very light lay structure, weighing as little as $\frac{1}{10}$ of the weight of a conventional lay assembly.

Another object is to provide greater clearance between the lay and the harness.

A further object is to provide certain improvements in the form, construction and arrangement of the several parts by which the above-named and other objects may effectively be attained.

A practical embodiment of the invention is shown in the accompanying drawings, wherein

Fig. 1 represents a warp-wise vertical section through the lay, race plate and frame brace, showing the lay support, the reed being in beat-up position against the fell of the cloth;

Fig. 2 represents a view similar to Fig. 1, with the reed retracted and the race plate in shuttle-supporting position under the shed;

Fig. 3 represents a detail perspective view (parts being broken away) of one end of the lay and its supporting and driving means;

Fig. 4 represents a warpwise vertical section, showing in elevation the lay driving cam, followers and connecting rod;

Fig. 5 represents a detail view, similar to Fig. 4, showing the cam turned 180° from the position of Fig. 4;

Fig. 6 is a simple graph showing a recommended cycle of operation for the lay and its relation to the period of shuttle travel;

Fig. 7 represents a detail horizontal section through the cam and adjacent parts, taken on the line VII—VII of Fig. 4; and

Fig. 8 represents a warpwise vertical section showing an alternative form of lay support.

Referring to the drawings, it will be understood that the mechanism shown herein is particularly adapted for use in a loom having its shuttle boxes fixed to the frame and the picking mechanism likewise mounted on the frame independently of the lay.

The harness supporting and operating mechanism is indicated diagrammatically at 1, a shuttle box at 2, shuttle at 3 and a frame brace at 4. The upper and lower warp yarns 5' and 5'' are moved in any customary

2

manner to form the shed 6, and the woven cloth 7 extends toward a take-up roll (not shown) from the fell 8. The drive shaft 9 is mounted in the frame and driven in the usual manner. To the extent that only one side of the lay and associated parts may be shown and described, it will be understood that the opposite end comprises a mirror image of that shown, unless otherwise stated.

The lay includes end brackets 10 having a vertical part 10' and a lower offset part 10'', the form of the latter part being such that it can move freely in a horizontal direction past, and embracing, the frame brace 4, as clearly shown in Figs. 1 to 4. The reed-cap 11 is firmly fixed at its ends to the tops of the brackets 10 by means of the reed-cap clamps 12; the reed bed 13 being welded to the brackets and preferably including a channel-shaped part 13'' adapted to receive the bottom edge of the reed 14. Adjacent the reed, the race plate 15 is fixed to the offset parts of the brackets, its upper surface being disposed to lie as nearly as possible in the plane of the bottom of the shed.

In the form shown in Figs. 1 to 4 each bracket has a split mounting block 16 secured to its lower end and projecting outwardly therefrom, each such block being assembled on a slide rod 17 and fixed in its properly adjusted position thereon by means of the screws 16'. The rods 17 are slidably supported in elongated bushings 18 fixed on the frame brace 4, the bushings being preferably either made of, or lined with, a suitable anti-friction material. The drive end of each rod 17 is in the form of a clevis, by means of which it is pinned to the end of a stud 19 passing slidably through one end of a turnbuckle 20, the inner end of the stud being threaded and surrounded by a spring 21 adapted to bear against the inner end wall of the turnbuckle and against a washer and lock nut assembly 22 on the threaded end of the stud. The other end of the turnbuckle is threaded to receive the threaded stem 23 of the cam yoke 24.

The drive shaft 9 (a straight through top shaft without offsets) passing through the elongated opening 24' of the yoke, is provided with a bearing 26 serving to guide the yoke in a straight line path between its advanced and retracted positions. The shaft is slotted, as indicated at 27, and the more or less ovoid cam 28 and the reniform cam 29 are keyed to the shaft with their axes of symmetry lying in the same plane. The cam 28 bears against the roller 30 and causes the feed or beatup stroke of the lay, while the cam 29 bears against the roller 31 and acts to return the lay to its position of dwell for the passage of the shuttle (Fig. 6), the rollers 30 and 31 being mounted on opposite ends of the yoke. The cam assembly is secured in proper position on the drive shaft by means of a clamp 32 (which may conveniently be shaped to constitute a counterbalance for the cams) and a smaller clamp 33, the latter being spaced from the bearing 26 by means of a ring 34, and the cam 28 being spaced from the bearing by means of the spacer 35.

The frame brace 4 is provided with a stop 36 aligned with each of the lay brackets, the stops being adjustable (Fig. 4) in order to ensure proper positioning of the lay assembly at dwell, the adjustable stops cooperating with the action of the spring-loaded turnbuckle to obtain this result. On the forward (beat-up) stroke of the lay the turnbuckle part of the connecting rod assembly acts as a solid member. The spring 21 is sufficiently pre-loaded to overcome the inertia forces of the lay and its supports during the return stroke (toward the left in Figs. 1 to 4). Near the end of this stroke, resulting from the action of cam 29 on roller 31, the lay support brackets come against the stops 36 and are held there by the continuing action of the cam which causes the

spring to compress (Fig. 5), as the turnbuckle assembly stretches, the spring force serving to hold the lay assembly firmly in its proper position during the dwell part of the cycle. At this time, the shed is wide open, and it remains so during the entire shuttle flight so that chafing by the shuttle is minimized. Furthermore, since the shuttle is not obliged to force its way through a closing shed, the shuttle can be made lighter (e.g., of aluminum) or smaller while still carrying the same yardage of weft yarn, or can be designed to carry substantially greater yardage.

An alternative form of support is shown in Fig. 8, wherein the lay assembly is mounted on light weight tubular rods 37, the lower ends of which are clamped at 38 to a rocker shaft 39 at the base of the loom. Each lay bracket is operated through a connecting rod and cam drive assembly as described above, the only difference being that the lay motion is along a rather flat arc with the rocker shaft as its center instead of being in a straight line.

The desirable lightness of the lay assembly may result in part from the use of extruded metal shapes (e.g., of aluminum) for the reed cap 11, reed bed 13, and race plate 15, or some of them. The reed cap may be secured to the lay brackets by means of the quick-disconnect clamps 12, so that reeds can be interchanged rapidly and easily when desired. While the lay-driving cams and connecting rods are referred to as being duplicated on the right and left sides of the loom it should be noted that such duplication may be unnecessary in a narrow fabric loom, and the description and claims are to be read with this understanding.

In the structure disclosed, the usual cumbersome lay swords and heavy lay beam carrying shuttle boxes have been eliminated, thus aiding in the achievement of the objects previously enumerated. The beat-up stroke is greatly shortened, being only about half of that normally used, permitting the reed to beat-up, clear the shed and dwell in a smooth cycle, more than half of which may be occupied by the dwell, as shown in Fig. 6.

It will be understood that various changes may be made in the form, construction and arrangement of the several parts and in their mode of operation, without departing from the spirit and scope of the invention.

What we claim is:

1. A lay assembly and support for weaving looms having stationary shuttle boxes comprising, vertical end brackets, a reed assembly secured to and extending between said brackets, a race plate secured to and extending between said brackets, means supporting said brackets for reciprocating horizontal motion, driving means for reciprocating said brackets and the parts secured thereto between the beat-up position and a predetermined retracted position, and connecting rod assemblies connecting said driving means to said brackets, said connecting rod assemblies being resiliently variable in length.

2. A lay assembly and support according to claim 1 which includes a rigid and adjustable stop against which the lay assembly is firmly held in its retracted position.

5 3. A lay assembly and support according to claim 2 in which each connecting rod assembly contains a spring so disposed as to permit the length of the assembly to vary resiliently while the lay assembly is held against the stop.

4. A lay assembly and support according to claim 3 in which each connecting rod assembly is designed to have its length rigidly fixed during the beat-up stroke.

10 5. A lay assembly and support according to claim 2 in which the stop is so located as to limit the retracting motion of the reed to a position closely adjacent the shed.

15 6. A lay assembly and support according to claim 1 in which the loom includes a frame brace extending across the loom approximately beneath the fell of the fabric to be woven, in which the end brackets are so shaped as to partially embrace said frame brace, and which includes rigid and adjustable stops carried by said frame brace for engaging said brackets in the retracted position of the lay assembly.

20 7. In a lay assembly and support for weaving looms, a pair of end brackets each having an upper vertical part and a lower horizontally offset part, means for attaching a reed cap to the top of each vertical part, a race plate having its ends fixed on the offset parts and means for supporting said brackets for reciprocating horizontal motion.

30 8. A lay assembly and support according to claim 7 in which the support comprises a pair of horizontally disposed bushings, a pair of rods slideable therein and means for fixing the lower offset part of each bracket to one of said rods.

35 9. A lay assembly and support according to claim 7 in which the support comprises a rocker shaft at the base of the loom, a pair of substantially vertical rods having their lower ends pivoted on said rocker shaft, and means for fixing the lower offset part of each bracket to the upper end of one of said rods.

40 10. A lay assembly and support for weaving looms provided with stationary shuttle boxes and shuttle picking means comprising, a reed assembly and support therefor, driving means including a cam for reciprocating said reed assembly between the beat-up position and a predetermined dwell position close to the shed, and means including a stretchable connection between said cam and the reed support for holding said reed assembly in said dwell position at least during the entire shuttle flight.

45 11. A lay assembly and support according to claim 10 in which the reed assembly is held in dwell position during each sequence of shuttle picking, flight and boxing.
